WOMAN'S SHOE

Louis Fabian, 33—75 76th St., Jackson Heights, N.Y.

Filed Dec. 17, 1959, Ser. No. 58,708

Term of patent 14 years

(Cl. D7—5)

Fig. 1 is a side elevation of a shoe showing my new design, the side opposite thereto being similar in appearance; and

The essential features of the design reside in the portions shown in solid lines and comprise a heel covering that extends up over the rear counter of the shoe stopping short of the top thereof, substantially as shown.

I claim:

The ornamental design for a woman's shoe, as shown, and described.
